DOOR CHECK AND CLOSER

John Hines, South Norwalk, Conn., assignor, by
mesne assignments, to Reconstruction Finance
Corporation, New York, N. Y., a corporation of
the United States

Application July 29, 1946, Serial No. 686,804

12 Claims. (Cl. 16—52)

1

The subject matter of this invention is a door check adapted to be employed with either a right or left hand swinging door. In door checks of the type alluded to a flat band clock spring is employed. This spring is normally expanded or unwound and winds up when the door is opened when utilized in connection with either a right or left hand swinging door. Where the door check was assembled for a right hand swinging door and where it was desired to employ it in connection with a left hand swinging door, it was necessary to disassemble the door check, reverse the clock spring and thereafter reassemble the door check. A similar reversal of the clock spring was required in the matter of rendering effective the door check if assembled for a left hand swinging door for its conversion to a right hand swinging door. One object of the invention resides in the provision of a novel and improved door check requiring no disassembly or reassembly in the matter of converting the door check from a right hand swinging door to a left hand swinging door and vice versa. Another important object is to provide a serviceable door check adapted to be utilized for either a right or left hand swinging door without need of reversing the clock spring. A further object is to severally utilize both ends of the clock spring in the matter of winding up the clock spring, that is, in one instance this spring would be wound up from the innermost convolution and in another instance the spring would be wound up from the outermost convolution. Another object resides in the provision of superimposed discs having means adapted to be selectively driven by a driving disc rotated when the door is swung open counter-clockwise for a right hand swinging door or clockwise for a left hand swinging door, the driving disc being common to the selectively driven superimposed discs and in turn is actuated by the ratchet means rotated through the action of a swingable dog carried by a swingable arm responsive to the opening of the door. Another object is to provide means for retarding the unwinding or recoil of the spring on closing of the door. Other essential objects, features, and functional and structural advantages of the invention will appear from the following detailed specification taken with the accompanying drawings wherein:

Fig. 1 is a plan view of the door check according to my invention mounted on a right hand swinging door.

Fig. 1A is a view taken on the line 1A—1A of Fig. 1.

2

Fig. 2 is a view similar to Fig. 1 showing the door check mounted on a left hand swinging door.

Fig. 3 is a transverse sectional view taken on the line 3—3 of Fig. 1.

Fig. 4 is a sectional view on the line 4—4 of Fig. 3.

Fig. 5 is a plan view exhibiting the cover for the housing of the door check broken away to illustrate the internal construction depicting the door check in a neutral position.

Fig. 6 is a view similar to Fig. 5 illustrating the action of the driving disc on a companion driven disc at a time when a right hand swinging door is opened for winding up the clock spring from its innermost convolution.

Fig. 7 is a sectional view on the line 7—7 of Fig. 3.

Fig. 8 is a view similar to Fig. 5 but showing the action of a rotatable driving disc on another companion driven disc during opening of a left hand swinging door.

Fig. 9 is a horizontal sectional view of Fig. 7, but illustrating the clock spring winding up from its outermost convolution during opening of a left hand swinging door.

Fig. 10 is a perspective view of the ratchet.

Fig. 11 is a perspective view of the driving disc.

Fig. 12 is a perspective and broken view of the door check driven shaft.

Fig. 13 is a perspective view of the driven disc actuated by the driving disc on opening of a right hand swinging door.

Fig. 14 is a perspective view of the rotatable sleeve or bushing for winding up the clock spring from its innermost convolution, and

Fig. 15 is a perspective view of the driven disc for winding up the clock spring on opening of a left hand swinging door.

Illustrative of the embodiment disclosed the door check generally denoted DC is appropriately mounted on a bracket B desirably fastened to the jamb or frame J for the swinging door D. As shown in Fig. 1, the hinge H for the door is on the outside and to the right of the operator when the latter is facing the door. Thus when the operator opens the door from the outside, the door swings from left to right. Such type of opening may for purposes of description, be considered as a right hand opening or swinging door. In Fig. 2, hinge H is at the left of the operator when the latter is on the outside of the door and such type of door may be considered as a left hand opening or swinging door. In either case,

55

a lever L is appropriately swiveled to a bracket 10 suitably fastened to the door. Lever L is hinged at 11 to the swinging arm 12 provided with a hub 13 (Fig. 4) appropriately fastened or keyed to shaft S having its lower reduced end 14 journalled in the bearing 15 of a conventional hydraulic or oil filled inverted T-shaped cylinder C comprising housing HH.

Fastened to shaft S is the pinion G in mesh with a conventional and reciprocable rack R of a double acting piston or plunger (not shown) within cylinder C having an internally threaded annular flange 16 cooperating with the externally threaded portion 17 of a conventional packing gland broadly designated 18 also rotatably guiding shaft S. By the present arrangement, it follows that if door D be swung open, shaft S is rotated relative to the packing gland 18 and the housing HH and when the door is closed shaft S is rotated in a counter direction. The construction so far described is well known in the art.

Freely rotatable on shaft S is the ratchet 20 adapted to be actuated by the pawl or dog 21 swiveled or hinged to the swingable arm 12. If therefore pawl 21 is selectively thrown in mesh with ratchet 20, the latter is rotated in a counterclockwise direction (Fig. 6) as would be the case for a right hand hung door or in a clockwise direction (Fig. 8) in the case of a left hand swinging door. In either case the pawl 21 in order to be effective is initially thrown to be in advance of the arm 12 in the direction of its rotation. Ratchet 20 is provided with a cylindrical portion 22 rotatably guided in bearing 23 of the cover 23 fixedly but removably carried by the housing HH.

Depending from the cylindrical portion 22 is the hollow non-circular lug or key 24 removably fitting into a correspondingly shaped opening 25 of a driving disc DD provided with a depending and driving lug 26 common to and closely straddled by or interposed in the neutral position of the door check between the driven and depending lug 27 of the left hand or clockwise driven disc LD and the horizontal lug or ear 28 of the right hand or counterclockwise driven disc RD (Figs. 4 and 5).

Seated on the upper part of the packing gland 18 and rotatably surrounding shaft S is the hollow and cylindrical bushing or sleeve 30 provided with the reentrant slot 31.

Integral with bushing 30 is the square shaped boss or key 32 removably but closely receiving the correspondingly shaped opening 33 of the right hand or counterclockwise driven disc RD seated on annular shoulder 30' at the upper part of the bushing 30.

Extending upwardly from boss 32 and integral therewith is the hollow cylindrical or annular bearing or guide collar 34 rotatably receiving the wall of the circular opening 35 of the left hand driven disc LD removably seated on boss or key 32.

Surrounding bushing 30 and interposed between disc RD and gland 18 although in part seated on the latter is the relatively flat spiral band or clock spring BS having its innermost convolution 36 provided with a hook 37 anchored or desirably retained in the reentrant slot 31 of the bushing 30.

The outer convolution 38 of the band spring BS is provided with an offset terminal or hook 39 anchored to or interlocking with the laterally extending and offset fingers 40 of the depending lug 27 of the left hand driven disc LD.

By the herein arrangement the inner end of the band spring BS may be said to be hooked onto the rotatable bushing or sleeve 30 while the outer end of the band spring is hooked onto the depending lug 27 and more particularly the spaced fingers 40 thereof.

Normally the band spring BS is expanded or unwound and is held in such expanded relation by the retaining ring 41 disposed in part in the recess 42 (Fig. 4) defined by the offset fingers 40 or in other words the vertically spaced fingers 40 of depending lug 27 straddle the retaining ring 41 to maintain the latter in a located position about the outer convolution 38 of the band spring BS.

If it be assumed the door check DC is mounted on a right hand swinging door as illustrated in Fig. 1, the lever 12 is swung counterclockwise when the door is opened as indicated by arrow 43. Consequently shaft S is also driven or rotated counterclockwise upon opening of the door. However prior to opening of the door the driving lug 26 of disc DD (Fig. 4) is between lug 28 of disc RD and the depending lug 27 of the disc LD, the band spring BS is expanded, and both of the lugs 27 and 28 are urged by the band spring BS against the radially extending internally disposed boss or projection 44 of the hollow housing HH. In other words, the door check is in a neutral relation as shown in Figs. 4 and 5.

Once the door is opened, pawl 21 carried by the swinging arm 12 rotates the ratchet 20. For a right hand swing door, ratchet 20 is driven counterclockwise. Since the driving disc DD is locked or keyed to the ratchet, the latter is also driven counterclockwise. It follows that ear or lug 28 of the driven disc RD is rotatably displaced in a counterclockwise direction at which time however depending lug 27 of disc LD is abutting the stop or boss 44.

If disc RD is driven counterclockwise, sleeve or bushing 30 is also driven in a corresponding direction relative to shaft S in that the squared shaped boss 32 of the sleeve is locked within the squared shaped opening 33 of disc RD.

Rotation of bushing 30 in a counterclockwise direction causes nose 46 (Fig. 7) of bushing 30 to drive hook 37 of the innermost convolution of the band or clock spring BS and consequently 50 the latter winds up, that is, the band spring BS is tensioned by winding the latter from the inside until the door is fully swung open but during such operation depending lug 27 of disc LD is always abutting boss 44 (Figs. 4, 5 and 6) due 55 to the action of spring BS.

In case the door check DC is mounted on a left hand hung door (Fig. 2) and if the door be closed, the check is again in a neutral position as shown in Figs. 4 and 5. But the pawl 21 (Fig. 5) must 60 first be thrown to be in advance of the swinging arm 12 (Fig. 8). On opening of the door, arm 12 would move in a clockwise direction as indicated by the arrow 47 in Fig. 8. When the door is opened in Fig. 2, arm 12 due to the action of 65 pawl 21, rotates ratchet 20 in a clockwise direction. Since the driving disc DD is locked to ratchet 20, disc DD is now rotated in a clockwise direction and lug 26 of this disc abuts and drives the depending lug 27 of disc LD in a clockwise direction. It follows that disc LD which is 70 rotatably mounted on the cylindrical nipple or collar 34 is rotated in a clockwise direction relative to the sleeve or bushing 30.

Although lug 27 of the rotatable disc LD is 75 driven in a clockwise direction, lug or ear 28

of disc RD, however, remains in an abutting relation against the stop or boss 44 (Fig. 8) due to spring BS. Now as lug 27 is driven clockwise, offset fingers 40 drive the hooked portion 39 of band spring BS and hence winds this spring up from its outside convolution upon opening of the left hand swinging door.

By the present invention, it is apparent the door check is adapted for either a right or left hand swinging door without resorting to reversing the band spring. This is an important feature of my invention.

In all cases after the door has been opened the spring remains wound up until the door is released. If it be assumed that the door is of the right hand swing type (Fig. 1) that has been opened and released, the spring automatically re-coils or unwinds but such action is delayed to prevent slamming of the door. Upon expansion or unwinding of the clock spring, sleeve 30 (Fig. 7) is now rotated in a clockwise or in a reverse direction by the action of the spring. Consequently the driven disc RD is now reversely rotated and ear or lug 28 drives lug 26 of the driving disc DD (Fig. 6) towards its neutral position. If disc DD is rotated reversely, then ratchet 20 is correspondingly rotated. Hence through the action of pawl 21 the swingable arm 12 is retracted, thus reversely rotating shaft S which in turn retracts the reciprocable piston carrying rack R but since the latter is resisted in its retraction by the oil in the cylinder C, a braking action is created so that the door is caused to close slowly. This braking action also retards unwinding of spring BS.

Where the left hand swinging door is opened and released, the clock spring also unwinds and acts on lug 27 (Fig. 8) of the driven disc LD, causing the latter to rotate towards its neutral position against boss 44 of the housing HH. Therefore disc DD is reversely rotated. Ratchet 20 is likewise reversely rotated and through the action of pawl 21, arm 12 is retracted reversely rotating shaft S and consequently rack R is retracted but against the resistance of the oil within cylinder C, thus cushioning closing of the door. And of course by such action the unwinding of the spring BS is retarded.

For purposes of specification, discs RD and LD each may be considered as a driven member and disc DD as a driving member. Bushing 30 and arm or lug 27 of disc LD each may be considered as a keeper for retaining or interlocking with the reflexed end portions or hooks 37 and 39 of spring BS. Of course nose or lip 46 of bushing or sleeve 30 winds up the spring from its inner end. The bushing 30 may be said to be locked, coupled or keyed to the driven means or disc RD and the ratchet 20 is coupled or locked to the driving disc DD. Boss 24 is common to the driven members or discs LD and RD and limits their retraction when a left hand hung door or a right hand hung door is closed respectively.

Various changes may be made in the details of construction and arrangement of parts without departing from the spirit of the invention or sacrificing any of the advantages thereof inherent therein.

I claim:

1. A door check for cushioning the closing of a door, a shaft within said check, a normally unwound spiral spring about said shaft, keeper means for retaining the inner end of said spring, means about said shaft for retaining the outer end of said spring, rotatable means responsive

to the opening of said door for actuating said keeper means for winding up said spring from said inner end, and means independent of said rotatable means for actuating the latter for winding up said spring from said outer end.

2. A door check to cushion the closing of a door, a shaft within said check, a normally unwound spring about said shaft, keeper means for retaining the inner end of said spring, means about said shaft for retaining the outer end of said spring, rotatable means responsive to the opening of said door for actuating said keeper means for winding up said spring from said inner end, displaceable means independent of said rotatable means for winding up said spring from said outer end, stop means to resist shifting of said displaceable means during winding up of said spring from said outer end, and stop means to resist shifting of said rotatable means during winding up of said spring from said inner end.

3. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft, a normally unwound spring surrounding said bushing and having an inner end retained by the latter, a driven member rotatably mounted relative to said shaft and having means for retaining the outer end of said spring, driven means surrounding said shaft and having means for actuating said bushing, a ratchet rotatable relative to said shaft, pivoted means carried by said swingable means for rotating said ratchet upon opening of said door, and a driving member having means actuated by said ratchet and including means for rotatably displacing said driven member relative to said driven means to wind up said spring from said outer end or for rotatably displacing said driven means relative to said driven member to wind up said spring from said inner end.

4. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft, a normally unwound spring surrounding said bushing and having an inner end retained by the latter, a driven member rotatably mounted relative to said shaft and having depending means for retaining the outer end of said spring, driven means surrounding said shaft and having means coupled to and for actuating said bushing, a ratchet rotatably surrounding said shaft, pivoted means carried by said swingable means for rotating said ratchet upon opening of said door, and a driving member having means keyed to said ratchet and including means for rotatably displacing said driven member relative to said driven means to wind up said spring from said outer end or for rotatably displacing said driven means relative to said driven member to wind up said spring from said inner end.

5. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft and embodying a non-circular boss having a bearing, a normally unwound spring surrounding said bushing and having an inner end retained

by the latter, a driven member rotatably guided by said bearing and having means for retaining the outer end of said spring, driven means interlocked with said boss, a ratchet rotatable relative to said shaft, pivoted means carried by said swingable means for rotating said ratchet upon opening of said door, and a driving member having means actuated by said ratchet and including means for rotatably displacing said driven member relative to said driven means to wind up said spring from said outer end or for rotatably displacing said driven means relative to said driven member to wind up said spring from said inner end.

6. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft, a normally unwound spring surrounding said bushing and having an inner end retained by the latter, a driven member rotatably mounted relative to said shaft and having means for retaining the outer end of said spring, driven means surrounding said shaft and having means for actuating said bushing, a ratchet rotatable relative to said shaft, pivoted means carried by said swingable means for rotating said ratchet upon opening of said door, a driving member having means actuated by said ratchet and including depending means for rotatably displacing said driven member relative to said driven means to wind up said spring from said outer end or for rotatably displacing said driven means relative to said driven member to wind up said spring from said inner end, and stop means projecting from said cylinder and straddled by said driven member and driven means to resist displacement of said driven member relative to said driven means upon rotation of the latter or resist displacement of said driven means relative to said driven member upon rotation of the latter.

7. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft and including a non-circular boss having a bearing, a normally unwound spring surrounding said bushing and having an inner end retained by the latter, a driven member rotatably guided by said bearing and having means for retaining the outer end of said spring, driven means having means interlocked with said boss, a ratchet rotatable relative to said shaft and having a depending boss, pivoted means carried by said swingable means for rotating said ratchet upon opening of said door, and a driving member having means actuated by said depending boss and including means for rotatably displacing said driven member relative to said driven means to wind up said spring from said outer end or for rotatably displacing said driven means relative to said driven member to wind up said spring from said inner end.

8. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably guided by said shaft and including a key having a cylindrical and upstanding bearing, a normally unwound

spring about said bushing and having an inner end retained by the latter, a driven member rotatably guided by said bearing and having means for retaining the outer end of said spring, driven means having a non-circular opening including walls interlocked with said key, a ratchet rotatable about said shaft and having a depending boss, pivoted means carried by said swingable means for rotating said ratchet relative to said shaft upon opening of said door, and a driving member having means actuated by said depending boss and including means for rotatably displacing said driven member relative to said driven means to wind up said spring from said outer end or for rotatably displacing said driven means relative to said driven member to wind up said spring from said inner end.

9. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft and including a non-circular boss having a bearing, a normally unwound spring surrounding said bushing and having an inner end retained by the latter, a driven member rotatably guided by said bearing and having depending means for retaining the outer end of said spring, driven means having means interlocked with said boss for bodily rotating with said bushing, a ratchet rotatable relative to said shaft and having a depending key, pivoted means carried by said swingable means for rotating said ratchet upon opening of said door, and a driving member having means actuated by said depending key and including means for rotatably displacing said driven member relative to said driven means to wind up said spring from said outer end or for rotatably displacing said driven means relative to said driven member to wind up said spring from said inner end.

10. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft and including a non-circular boss having a terminal and cylindrical bearing, said bushing having a slot and a lip, a normally unwound spring surrounding said bushing and having an inner end disposed in part in said slot and interlocked with said lip, a driven member having an annular portion rotatably guided by said bearing and having depending means for retaining the outer end of said spring, driven means having means interlocked with said boss, a ratchet rotatable relative to said shaft and having a depending boss, pivoted means carried by said swingable means for rotating said ratchet upon opening of said door, and a driving member having means actuated by said depending boss and including means for rotatably displacing said driven member relative to said driven means to wind up said spring from said outer end or for rotatably displacing said driven means relative to said driven member to wind up said spring from said inner end.

11. A door check wherein a shaft is rotatably sustained in an hydraulic cylinder for reciprocably guiding a piston carrying rack adapted to be actuated by a gear on said shaft rotated by swingable means secured to a door and said shaft; comprising, a bushing rotatably surrounding said shaft and including a non-circular boss having

a bearing, a normally unwound spring surrounding said bushing and having an inner end retained by the latter, a driven member rotatably guided by said bearing and having depending means interlocked with the outer end of said spring, driven means having means interlocked with said boss, a ratchet rotatable relative to said shaft and having a depending boss, pivoted means carried by said swingable means for rotating said ratchet upon opening of said door, and a driving member having means actuated by said depending boss and including depending means for rotatably displacing said driven member relative to said driven means to wind up said spring from said outer end or for rotatably displacing said driven means relative to said driven member to wind up said spring from said inner end.

12. A door check wherein a shaft is rotatably sustained in an hydraulic cylinder for reciprocably guiding a piston carrying ratchet adapted to be actuated by a gear on said shaft rotated by swingable means secured to a door and said shaft; comprising, a bushing rotatably surrounding said shaft and including a non-circular boss having an annular bearing, a normally unwound spring surrounding said bushing and having an inner end retained by the latter, a driven disc rotatably

guided by said bearing and having a depending lug including spaced fingers for retaining the outer end of said spring, a driven disc having means interlocked with said boss and including an ear, a ratchet rotatable relative to said shaft and having a depending boss, pivoted means carried by said swingable means for rotating said ratchet upon opening of said door, and a driving disc having means actuated by said depending boss and including an extension for abutting said depending lug for rotatably displacing said first mentioned disc relative to said driving disc to wind up said spring from said outer end or for displacing said ear for rotatably actuating said driving disc relative to said second mentioned disc to wind up said spring from said inner end.
